COMBINED FERRULE AND INSULATION HOLDER FOR WIRES

Ulrich C. Dunaway, St. Louis, Mo., assignor to
 James R. Kearney Corporation, St. Louis,
 Mo., a corporation of Missouri

Application August 7, 1935, Serial No. 35,086

2 Claims. (Cl. 173—269)

This invention relates generally to ferrules and insulation holders for electrical wires, and more specifically to an improved device which provides a combined ferrule and insulation holder adapted for attachment to an end portion of an electrical conductor of the extra flexible stranded type provided with heavy rubber insulation, the predominant object of the invention being to provide a device of this sort which at once provides the 10 flexible strands at an end of such a conductor with a protecting sleeve well adapted to receive in contact therewith set screws and other clamping elements, and which includes means for holding and retaining in place the insulated portion of the conductor which is located adjacent to the stranded end portion of said conductor that is received by said ferrule.

As is generally known by persons familiar with such matters, electrical conductors are frequently attached to clamps and other articles of electrical equipment with the aid of set screws and like clamping elements. In the case of electrical conductors of the type including very flexible strands of conducting material enclosed within heavy rubber insulation, it has been found necessary to provide some means, such as a ferrule, for enclosing the flexible stranded end portion of the conductor so that secure mechanical and positive electrical contact may be obtained between the clamping elements and the conductor. Need has also been felt for some means for clamping over the insulation of the conductor so as to prevent the very flexible strands of the conductor from breaking at the end of the insulation due to extreme flexibility at that point when the end of the conductor is clamped in place when in use.

I have therefore evolved the improved device disclosed herein which, briefly stated, comprises a unitary element in which is combined a ferrule for receiving the flexible strands of the conductor so that set screws and other clamping elements may be applied thereto, and means for receiving and clamping in place the insulated portion of the conductor which is located immediately adjacent to the stranded ferrule-receiving portion of the conductor. Thus the improved device provides for a conductor adequate ferrule means for receiving in contact therewith set screws and other clamping elements, which ferrule means protects the flexible strands of the conductor from injury from the clamping elements and provides for secure and positive mechanical and electrical connection between the conductor and said clamping elements. Also, the improved device provides

for so holding the insulated portion of the conductor located adjacent to the ferrule-receiving stranded portion thereof as to prevent such movement of the conductor as would tend to break the flexible strands at the end of the insulation. 5

Fig. 1 is a front elevation of the improved device applied to a fragment of an electrical conductor.

Fig. 2 is a side elevation of the structure illustrated in Fig. 1. 10

Fig. 3 is a horizontal section on line 3—3 of Fig. 1.

In the drawing, wherein is shown for the purpose of illustration, merely, one embodiment of the invention, A designates the improved device generally. The device A comprises a head 1 which includes an intermediate portion 2 from which a tapered portion 3 is extended. Projected outwardly from the tapered portion 3 is a sleeve portion 4, said sleeve portion preferably, though not necessarily, also being slightly tapered. The intermediate portion 2 and the tapered portion 3 have formed therethrough a continuous opening 5, and this opening communicates with a slightly larger opening 6 formed through the sleeve portion 4. Fixedly seated in any suitable manner in the opening 6 formed in the sleeve 4 is a length of tubing 7 formed of copper or other good electrical conducting material, the opening through said length of tubing being of substantially the same diameter as the opening 5 formed through the intermediate and tapered portions 2 and 3 of the head 1. 20 25 30 35 40 45 50 55

Extended from the intermediate portion 2 of the head 1 in the opposite direction to the direction of extension of the tapered portion 3 and the sleeve 4 is a leg 8 which is of arcuate cross-section, as shown in Fig. 3. The leg 8 has formed thereon ears 9 which extend outwardly from said leg in opposite directions, said ears having screw-threaded openings 9' formed therethrough. Associated with the leg 8 of the head 1 of the device A is a clamping element 10, this clamping element also being of arcuate cross-section so as to correspond to the cross-sectional shape of the leg 8 of the head 1. The clamping element 10 is provided with outwardly extended ears 11 which are projected in opposite directions, said ears being aligned with the ears 9 of the leg 8. Also, the ears 11 of the clamping element 10 are provided with smooth openings 12 which are aligned with the openings 9' formed through the ears 9 of the leg 8. The openings 12 of the ears of the clamping element 10 and the openings 9' of the ears of the leg 8 receive clamping screws 13 which 55

pass through the smooth openings 12 of the ears of the clamping element 10 and are screwed into the screw-threaded openings 9' of the ears of the leg 8 so as to draw said clamping element into 5 clamping relation with respect to the leg 8.

In the use of the improved device an exposed stranded end portion S of an electrical conductor C is passed through the opening 5 formed in the head 1 of the device and is extended into the 10 opening through the length of tubing 7, said exposed stranded end portion of said conductor being soldered within said tubing. The clamping element 10, which is detached from the leg 8 when a conductor is being applied to the device 15 A, is then arranged in place and the clamping screws 13 are passed through the openings 12 of the ears of the clamping element and are screwed into the openings 9' of the ears of the leg 8 to securely clamp the insulated portion of the conductor C between the arcuate portions of the 20 clamping element and the leg. Thus the length of tubing 7 provides a ferrule which encloses the stranded end portion of the conductor, and this length of tubing may be introduced into a 25 clamp or other element of electrical equipment and receive set screws or other clamping elements in contact therewith to provide secure mechanical and positive electrical connection between the conductor and said element of electrical equipment. Also because the insulated portion 30 of the conductor is clamped and held in place by the clamping element 10 and the leg 8, no movement is permitted at the point where the exposed stranded end portion S extends from 35 the insulation R of the conductor, hence breaking of the strands of the conductor at that point because of movement of the conductor is prevented.

I claim:

40 1. A device of the class described, comprising a unitary structure including a cylindrical head, said head being provided with an integral sleeve portion at one end of the main body portion thereof of reduced diameter and having an integral 45 substantially semicircular extension at its opposite end the outer radius of which is substantially the same as the outer radius of the main body portion of said head, said head and sleeve portion having a continuous opening 50 formed therethrough, a hollow element providing

a ferrule which is fixedly supported in the opening formed in said sleeve portion and extends outwardly beyond said sleeve portion, said hollow element being adapted to receive an exposed stranded end portion of an electrical conductor, an arcuate clamping element associated with said extension in a manner to clamp an insulated portion of the electrical conductor between said clamping element and said extension so as to prevent movement of the clamped insulated portion of the conductor with respect to the stranded end portion thereof, and clamping bolts for drawing said clamping element toward said extension so as to clamp the insulated portion of the electrical conductor therebetween. 5

10 2. A device of the class described, comprising a unitary structure including a cylindrical head, said head being provided with an integral sleeve portion at one end of the main body portion thereof of reduced diameter and having an integral substantially semicircular extension at its opposite end the outer radius of which is substantially the same as the outer radius of the main body portion of said head, said head and sleeve portion having a continuous opening 20 formed therethrough, a hollow element providing a ferrule which is fixedly supported in the opening formed in said sleeve portion and extends outwardly beyond said sleeve portion, said hollow element being adapted to receive an exposed stranded end portion of an electrical conductor, an arcuate clamping element associated with said extension in a manner to clamp an insulated portion of the electrical conductor between said clamping element and said extension so as to 25 prevent movement of the clamped insulated portion of the conductor with respect to the stranded end portion thereof, said clamping element having an outer radius substantially the same as that of the main body portion of the head 30 and the arcuate outer surface of the clamping element being substantially aligned longitudinally of the device with respect to the arcuate outer surface of the main body portion of the head, and clamping bolts for drawing said clamping element toward said extension so as to clamp the insulated portion of the electrical conductor 35 therebetween. 40
